WILLIAM ERWIN, OF PHILADELPHIA, PENNSYLVANIA.

TYPE-WRITER TABULATOR AND BILLING DEVICE.

1,174,058.

Specification of Letters Patent.

Patented Mar. 7, 1916.

Application filed November 13, 1913. Serial No. 800,777.

To all whom it may concern:

Be it known that I, WILLIAM ERWIN, a citizen of the United States, residing at No. 4844 Cedar avenue, in the city of Philadelphia, in the county of Philadelphia and State of Pennsylvania, have invented a new and useful Type-Writer Tabulator and Billing Device, whereby in addition to all of the conveniences of a decimal or denominating tabulator is superadded the ability to just as easily and surely select any tenth letter-space, or any individual letter-space at which the carriage of the type-writer shall stop, thus generally avoiding the use of movable tabulator-stops, of which a clear and accurate description is presented by the following specification and the accompanying drawings, which form a part of it.

Figure 1, is a central, vertical, front-to-rear sectional view of an L. C. Smith & Bros. typewriter, to which this tabulator is applied, tabulator key No. 6, and tabulator lever No. 6, being shown; Fig. 2, is a plan view of the device; Fig. 3, is a front view of the tabulator rack, the right hand end being broken away; Fig. 4, is a side view of one of the rocking arms; Fig. 5, is a front view of the escapement releasing lever; Fig. 6, is a side view (a) of the rear end of one of the carriage arms which support the tabulator rack, (b) a side view of rack raising and lowering lever, and (c) a view of one end of rack raising and lowering rod; Fig. 7, is a front (a) and a side (b) view of one of the rear supports of the tabulator levers; Fig. 8, is a side view of a movable tabulator stop; Fig. 9, is a view of a modified form of the escapement releasing lever.

I have shown this tabulator as applied to an L. C. Smith & Bros. typewriter, though it or any of its various features may be applied to other types of typewriting machines. This tabulator is preferably placed in the typewriter in such position that its keys are alined directly back of and slightly higher than the upper or rear bank of keys of the machine, as shown in Fig. 1. Then the shafts of the tabulator levers will range horizontally and slantingly backward toward each other underneath the type-bars, until at the rear of the machine they are brought quite together, and their rear ends, sharply bent, will rise perpendicularly or nearly perpendicularly behind the platen to

about its level, and the tabulator rack will also occupy about the same level as the platen.

The tabulator keys, ten in number, are oblong from front to rear, and are pivoted at the upper part of their centers upon rod 1, shown with broken ends, which extends from side to side of the frame of the machine. These keys are numbered from 1 to 10 inclusive from left to right upon their rear ends, they are marked upon their centers to indicate from left to right the decimal point and the denominations and denominational separating points regularly arising therefrom, and are numbered from 1 to 10 inclusive from right to left upon their front ends. The upper surfaces of the tabulator keys may be curved upward at their ends to give a good finger hold, as shown at 2 in Fig. 1. At the center of each key is a downward extension 3, terminating in a joint 4 with the front end of the tabulator lever. This joint supports the front end of the tabulator lever.

The shafts 5 of the tabulator levers are directed backward from the keys horizontally in a slanting direction toward each other, so that their rear ends approximating each other, bent sharply at the rear of the machine, and rising perpendicularly or nearly perpendicularly, pass through opening 7 in top plate 8 of the machine, and terminate in two branches 9 and 10 at about the platen level. The terminal branches of the tabulator levers are made exactly one letter space thick, they rest in contact with each other, and are supported by a tabulator lever support 11, fastened upon top plate 8 of the machine at each side of said branches, and a bolt 12 passing from one support to the other through slots 13 in the tabulator levers just below the branches. Slot 13 allows, and by its length limits, a backward or forward sliding motion of a tabulator lever, upon depression of either end of the lever's tabulator key, and spring 14, one for each tabulator lever, (made thick and stiff to avoid vibration), vertically attached by its lower end to the front edge of the front cross member of the frame of the machine, engaging at its upper end the lower edge of the front end of the tabulator lever, maintains the lever in central position when at rest, maintains the tabulator key at a level

when at rest, and restores both to their first position after either end of the key has been depressed.

The front branch 9 of each tabulator lever is provided at the rear edge of its upper end with a stop 15 facing toward the right, beveled upon its opposite side, which may be projected backward into the path of one of the permanent tabulator rack stops 16 upon the front surface of tabulator rack 18, when the front end of a tabulator key is depressed, with the tabulator rack in its raised position as shown in Fig. 1, or into the path of one of the movable stops 17 when the tabulator rack is in its depressed position as shown by dotted lines in Fig. 1. Below stop 15 is a recess 19 cut out of the rear edge of branch 9 for the purpose of allowing the permanent tabulator rack stops 16 to pass the branch when the rack is depressed for engagement of movable stops 17 with stop 15 upon depressing the front end of a tabulator key. Upon the front edge of each branch 9 at the same level is a wedge-shaped forwardly projecting lever 23, level upon its upper surface, adapted to depress a rod 24 passing from the front end of one rocking arm 25 to the other, when the tabulator lever is projected forward by depressing the rear end of a tabulator key.

The rear branch 10 of each tabulator lever, made somewhat narrower than branch 9, rises slightly higher than branch 9, and is provided with a forwardly projecting stop 20 facing toward the right, beveled upon its opposite side, and set at different levels upon the different levers; that upon the left hand lever is set highest at a level to engage with permanent stop 5 $\frac{1}{4}$ or 10 $\frac{1}{4}$ upon the rear surface of tabulator rack 18, when it is projected forward by depressing the rear end of key marked 1 upon its rear end, that upon the right hand lever is set lowest at a level to engage with permanent stop 10 $\frac{1}{4}$ upon the rear surface of the tabulator rack, when it is projected forward by depressing the rear end of key marked 10 upon its rear end, and the intermediate stops upon the intermediate levers are set at regularly graded levels between 1 and 10 for engagement with correspondingly graded permanent stops upon the rear surface of the tabulator rack at 11 letter spaces apart, and numbered by their letter space position upon said rack. Therefore each stop 20 will engage only with its own special stop upon the rack, and will allow all others to pass.

At the upper end of each branch 10 is a forward projection 21, which occupies a lower level than raising and lowering rod 40 when the tabulator rack 18 is in its elevated position, but when the rack is depressed for use of the movable tabulator

rack stops 17, projections 21 are at a level to abut against rod 40, and thus prevent the unintentional or accidental use of the rear ends of the tabulator keys when the tabulator rack is thus depressed. Upon the rear edge of each branch 10 at the same level is a wedge-shaped backward projecting lever 26, level upon its lower surface, adapted to raise a rod 27 passing from the rear end of one rocking arm 25 to the other, when the tabulator lever is projected backward by depressing the front end of a tabulator key.

Fastened to the upper surface of the top plate 8 of the machine, and holding in apposition the terminal branches of the tabulator levers at the center of the rear part of the machine, is a tabulator lever support 11 upon each side of the approximated branches of the tabulator levers. These supports have upward branches to correspond with and cover upon the outside the branches of the tabulator levers, and are connected to each other by rod 12, which passes through slots 13 of the tabulator levers, and supports their rear ends.

A rocking arm 25 is pivoted at its center upon the end of rod 12 at the outer side of each support 11. At the front end of these arms is a connecting rod 24, and at their rear ends is a connecting rod 27. Rods 24 and 27 are provided with ten friction rollers 28 each, which are exactly one letter space wide, and are kept opposite their respective levers 23 and 26 of the tabulator lever branches, by means of sleeves 29, which fill the spaces between the outer friction rollers and the ends of the rocking arms.

Pivoted upon the ends of rod 24 are the arms of downward depending escapement releasing lever 30, which passes through an opening (not shown) in top plate 8 of the machine, and rests a short distance directly above but not touching the extremity 35 of escapement wheel release bell crank (only the extremity 35 being shown).

From each end of the carriage 34, a curved arm 37, with its convexity directed upward, extends backward to suspend the tabulator rack 18 equidistantly between the branches of the tabulator levers. At the rear end of each arm 37 is a lateral vertical slot 38, adapted to receive one end of the tabulator rack 18, and allow its vertical adjustment therein. Opening from the rear of slot 38 is a horizontal slot 39, adapted to receive a crank-pin of raising and depressing rod 40, and allow its front-to-rear adjustment therein. Rod 40, terminating in a crank at each end, lies along the upper rear surface of the tabulator rack throughout its length, to which it is secured by a journaled support 41 near each end. The crank-pin at each end of rod 40 rests in slot

39, and its position is controlled by adjusting lever 42, whose slot 43 allows it to slip upon the crank-arm of rod 40, where it is retained between carriage arm 37 and rod 5 support 41. Manipulation of this lever raises and lowers the tabulator rack for use of stops 16 or 17 as may be chosen. For short or medium length carriages one lever 42 is sufficient, but for long carriages permitting a possible twist of rod 40 because of its length, a lever 42 is placed at each end of the tabulator rack, when both levers are used simultaneously to raise or lower the tabulator rack.

15 The tabulator rack 18, is supported at its ends in slots 38 of carriage arms 37, by the crank ends of rod 40. From its upper edge, extending downward upon its front and rear surfaces far enough to give support to 20 movable stops 17, are grooves or recesses 17^a placed one letter space apart throughout its length. Into these grooves may be inserted a movable stop 17 at every space along the tabulator rack where it may be 25 desired to stop the carriage by means of the tabulator. One leg of the movable stops is made wider than the other, and is placed at the front of the tabulator rack for engagement with one of the tabulator lever 30 stops 15.

Upon the front surface of the tabulator rack are placed in a horizontal line, permanent stops 16 facing toward the left, ten letter spaces apart throughout its length, 35 adapted to stop the carriage at the denominational letter spaces. By its crank ends rod 40 is adapted to hold tabulator rack 18 in a raised position for use of permanent stops 16, or in a depressed position for use 40 of movable stops 17 as may be chosen, by the use of adjusting lever 42. Upon the rear surface of the tabulator rack is placed a series of permanent stops facing toward the left, which are placed eleven letter 45 spaces apart, and are numbered by their letter space position upon the rack, commencing with 5₁. Upon carriages having more than 105 letter spaces the series terminates at the tenth stop at space 104₁, and a 50 new series begins at space 105₁. Series corresponding to the first are continued to the end of the tabulator rack. The first stop of each series, that is 5₁, 105₁, 205₁, etc., is placed with its upper edge at the level of 55 the upper edge of stops 16 upon the front surface of the tabulator rack, and each succeeding stop is placed with its upper edge very slightly lower than the lower edge of the last preceding stop for a working 60 distance between the levels of the several stops.

All tabulator rack stops are placed so as to halt the carriage about $\frac{3}{4}$ of a letter space in advance of the intended stop of the carriage, for the purpose of insuring stepping

dog 31 full time to engage wheel 32 after the tabulator key has been released.

The greatest depth of the tabulator rack is at the tenth stop of each series of permanent stops upon its rear surface, its lower edge being cut away from the left side of each stop level to the next preceding stop, as shown in Fig. 3, this figure being placed upright to economize space upon the drawing. No novelty is claimed for the movable stops, or their manner of attachment to the tabulator rack. Adjusting lever 42, occupying a depending position when the tabulator rack is in its raised position, is swung backward and upward in a half circle to depress the tabulator rack, and vice versa to raise it.

When the front end of a tabulator key is depressed, the tabulator lever is moved backward by a sliding motion, lever 26 of branch 10 of the tabulator lever raises rod 27, and with it the rear ends of rocking arms 25. Thus the front ends of the rocking arms are depressed, and with them the escapement releasing lever 30 which presses downward the extremity 35 of the escapement wheel release bell crank, which in turn forces stepping dog 31 out of engagement with escapement wheel 32, and allows a free run of the carriage 34 until 95 intercepted by the engagement of stop 15 with one of the permanent stops 16 upon the front of the tabulator rack when it is in its raised position, or with one of the movable stops 17 when the tabulator rack 100 is in its depressed position. When the tabulator key is released spring 14 restores it to its level position, and the tabulator lever to its central position upon bolt 12, and spring 36 restores the rocking arms to 105 their level position, thus returning escapement releasing lever 30 to its original free position, while a spring (not shown) returns stepping dog 31 into engagement with escapement wheel 32. When the rear end 110 of a tabulator key is depressed, the tabulator lever is moved forward by a sliding motion, lever 23 of branch 9 of the tabulator lever depresses rod 24, and with it the front ends of rocking arms 25 and escapement releasing lever 30, escapement wheel release bell crank 35, and stepping dog 31, which releases escapement wheel 32, and allows a free run of the carriage 34 until 115 intercepted by the engagement of stop 20 with its own permanent stop upon the rear surface of the tabulator rack. When the tabulator key is released springs 14 and 36 return the tabulator key, the tabulator lever, the escapement releasing lever, and the 120 rocking arms to their first position, and the spring of the stepping dog returns it into engagement with the escapement wheel, in exactly the same way as is done when the front end of a tabulator key is released 125 130.

4
after being depressed. In every operation of this tabulator, escapement releasing lever 30 has a certain distance to travel before engaging extremity 35 of the escapement wheel release bell crank, and then both have a still further distance to travel before they release stepping dog 31 from escapement wheel 32, thus insuring the projection of one of the stops 15 or 20 into the path of 10 a tabulator rack stop before wheel 32 is released; and likewise retaining this engagement until after stepping dog 31 has returned into engagement with wheel 32.

In other typewriting machines, where a 15 free running release of the carriage is secured by depressing a part, such as a rack-bar or allied part of the machine, lever 30 may operate such release without departing from its essential principle of construction 20 or operation as above described; and in typewriting machines where usch release of the carriage is secured by raising any part of the mechanism out of engagement, a hook upon the lower end of lever 30, as indicated 25 by 30^a in Fig. 9, may readily accomplish this purpose by inverting the levers 23 and 26 of the tabulator lever branches, as shown by dotted lines 33 and 44 in Fig. 1. In this case operation of the tabulator levers will 30 raise the front ends of rocking arms 25 and with them lever 30.

In using this tabulator, with the tabulator rack in its raised position, the operator may 35 select any tenth or columnar space in the tabulator rack series beyond that occupied by the carriage, or in the next series following of a lower denomination than is occupied by the carriage, by depressing the rear end of the tabulator key which bears upon 40 its rear end the figure contained in the second denominational place of the number desired.

To illustrate:—Supposing the carriage is standing at any space between 40 and 50, 45 and it is desired to stop it at 60, or 70, or 80, or 90, or 100, depress the rear end of key marked upon its rear end 6, or 7, or 8, or 9, or 10 respectively; or should it be desired to stop the carriage at space 110, or 120, or 130, or 140, depress the rear end of key marked 50 on its rear end 1, or 2, or 3, or 4 respectively.

A free run of the carriage for more than 100 letter spaces can scarcely be desired, because of the detrimental shock to the machine of 55 so long a run, besides tabulating work seldom if ever requires a free run of such length, but if it is desired it can be obtained by a second depression of the rear end of the proper key.

60 In any case that a fraction of a columnar space is desired, the columnar space is first obtained as just described, and then the front end of a key is depressed which bears upon its front end the fractional number desired.

To illustrate:—Supposing the carriage is standing at any space between 40 and 50, and it is desired to stop it at 53, or 63, or 73, or 83, or 93, or 103, depress the rear end of key bearing upon its rear end 5, or 6, or 7, or 8, or 9, or 10, respectively, and when the carriage has stopped, depress the front end of key marked 3 upon its front end; or should space 113, or 123, or 133 be desired, 70 depress the rear end of key marked upon its rear end 1, or 2, or 3 respectively, and when the carriage has stopped, depress the front end of key marked 3 upon its front end.

Any other fraction of the columnar space is obtained by depressing the front end of the 80 corresponding key as above described. Thus it will be seen that, by this method the operator has perfect control of any selected columnar space within and including 100 letter spaces beyond the carriage, by the depression of the rear end of a single key, and may add to this any fraction of a columnar space by the added depression of the front end of the corresponding key. However, should it be desired to use this tabulator as a decimal or denominating tabulator with movable stops, the tabulator rack is first depressed by lever 42, the stops are set at the desired spaces, and then the front ends 85 of the keys are used in the usual manner of the keys, the rear ends of the keys being locked by rod 40 in its depressed position. But in this case it is necessary to halt the carriage 90 at each stop in rotation, whether each stop is always desired or not, whereas by the first described method the operator has the advantage of any choice within and including 95 100 spaces beyond the carriage, wherever it 105 may happen to be standing.

Having described my invention, what I claim as new, and desire to secure by Letters Patent, is—

1. A tabulating device for typewriters, 110 comprising means for releasing the typewriter carriage to permit it to run free, and then stopping the carriage, and pivoted rocking keys operating said means when rocked in either direction, substantially as 115 described.

2. A tabulating device for typewriters, comprising means for releasing the typewriter carriage to permit it to run free, and then stopping the carriage, and bifurcated 120 horizontally sliding tabulator levers which bear fixed stops at the same level upon one set of the bifurcations, and stops fixed at graduated levels upon the other set of bifurcations, controlling the operation of said 125 means, substantially as described.

3. A tabulating device for typewriters, comprising a tabulator rack adjustably secured to the typewriter carriage and bearing stops, and bifurcated horizontally sliding 130

tabulator levers bearing stops for controlling said rack stops, to release the carriage to permit it to run free, and then stop the carriage, substantially as described.

5. A tabulating device for typewriters, comprising means for releasing the typewriter carriage to permit it to run free, and then stopping the carriage, bifurcated horizontally sliding tabulator levers which 10 bear stops for controlling said means, and wedge-shaped members on said levers controlling the release of the carriage, substantially as described.

5. In a tabulating device for typewriters, 15 the combination of a vertically adjustable tabulator rack adapted to be secured to a typewriter carriage, and bearing adjustable stops, a series of fixed stops at the same level, and a series or more than one series of 20 fixed stops at graduated levels, with bifurcated horizontally sliding tabulator levers bearing stops for coöperating with the rack stops, for releasing the carriage to permit it to run free, and then stopping the carriage, substantially as described.

6. In a tabulating device for typewriters, the combination of a tabulator rack arranged to be adjustably secured to the typewriter carriage, and a series of fixed stops 30 on said rack located at the same level ten letter spaces apart throughout its entire length, with bifurcated horizontally sliding tabulator levers bearing stops for coöperating with the said stops on the rack for 35 releasing the carriage to permit it to run free, and then stopping the carriage, substantially as described.

7. In a tabulating device for typewriters, the combination of bifurcated horizontally 40 sliding tabulator levers which bear fixed stops at the same level upon one set of the bifurcations, and stops fixed at graduated levels upon the other set of the bifurcations, with a tabulator rack arranged to be adjustably secured to the typewriter carriage, and fixed stops upon said rack coöperating with the graduated tabulator lever stops, said rack stops being placed at graduated 50 levels eleven letter spaces apart in a series of ten stops, or multiples or fractions thereof in proper location and succession throughout the entire length of said rack according to its length, to release the carriage to permit it to run free, and then stop 55 the carriage at any tenth letter space, substantially as described.

8. A tabulating device for typewriters, comprising a tabulator rack bearing three sets of stops, said rack arranged to be adjustably secured to the typewriter carriage, bifurcated sliding tabulator levers bearing stops on both members of the bifurcations, engaging stops upon the rack and controlling the stopping of the carriage, and wedge-shaped members on said levers controlling

the release of the carriage, substantially as described.

9. In a tabulating device for typewriters, the combination of a carriage, supports thereon, a tabulator rack carried by said supports and vertically adjustable thereon, and three series of stops carried by said rack comprising adjustable stops, a series of fixed stops at the same level, and another series of fixed stops at graduated levels, substantially as described.

10. In a tabulating device for typewriters, the combination of a carriage, supports thereon, a tabulator rack bearing three sets of stops carried by said supports, a series 80 of sliding levers, each lever having a bifurcated end, and stops on both members of the bifurcated ends of the levers for engaging the stops upon the rack, substantially as described.

11. In a tabulating device for typewriters, the combination of a carriage, supports thereon, a tabulator rack bearing three sets of stops carried by said supports, a series 90 of sliding levers, each lever having a bifurcated end, and stops on both members of the bifurcated ends of the levers for engaging the rack stops, said bifurcated members at one side of the rack bearing stops at the same level, and the other bifurcated members bearing stops at graduated levels, substantially as described.

12. In a tabulating device for typewriters, the combination of a carriage, supports thereon, a tabulator rack carried by said supports, a series of sliding levers, each lever having a bifurcated end, and pivoted rocking keys operating said levers, substantially as described.

13. In a tabulating device for typewriters, the combination of a carriage, supports thereon, a tabulator rack bearing three sets of stops carried by said supports, a series of sliding levers, each lever having a bifurcated end, stops on both members of the bifurcated ends of the levers for engaging the rack stops, means for releasing the carriage to permit it to run free, and wedge-shaped members on the opposite sides of said levers compelling the operation of said means when the levers are moved in either direction, substantially as described.

14. In a tabulating device for typewriters, the combination of a carriage, supports thereon, a tabulator rack carried by said supports, a series of sliding levers, each lever having a bifurcated end, pivoted rocking keys operating said levers, means for releasing the carriage to permit it to run free, and wedge-shaped members on the opposite sides of said levers compelling the operation of said means when the levers are moved in either direction, substantially as described.

15. A tabulating device for typewriters,

- comprising means for releasing the typewriter carriage to permit it to run free, and then stopping the carriage, and bifurcated sliding levers controlling the operation of 5 said means, said levers having registering slots therein, and a rod extending through all of the slots and compelling the levers to move horizontally, substantially as described.
- 10 16. A tabulating device for typewriters, comprising means for releasing the typewriter carriage to permit it to run free, bifurcated sliding levers controlling said means, stops on the levers arranged to stop 15 the carriage, said levers having registering slots therein, and a rod extending through all of the slots and compelling the levers to move horizontally, substantially as described.
- 20 17. A tabulating device for typewriters, comprising a rack bearing three sets of stops, arranged to be adjustably secured to the typewriter carriage, bifurcated sliding levers bearing stops upon their bifurcations en- 25 gaging the stops upon the rack and controlling the stopping of the carriage, wedge-shaped members on said levers controlling the release of the carriage, said levers having registering slots therein, and a rod ex- 30 tending through all of the slots and compelling the levers to move horizontally, substantially as described.
18. In a tabulating device for typewriters, the combination of a carriage, supports 35 thereon, a tabulator rack bearing three sets of stops, carried by said supports, a series of sliding levers, each lever having a bifurcated end, stops on both members of the bifurcated ends of the levers for engaging the 40 stops upon the rack, said levers having registering slots therein, and a rod extending through all of the slots and compelling the levers to move horizontally, substantially as described.
- 45 19. In a tabulating device for typewriters, the combination of a carriage, supports thereon, a tabulator rack carried by said

supports, a series of sliding levers, each lever having a bifurcated end, pivoted rocking keys operating said levers, said levers having 50 registering slots therein, and a rod extending through all of the slots and compelling the levers to move horizontally, substantially as described.

20. In a tabulating device for typewriters, the combination of a carriage, supports thereon, a tabulator rack bearing three sets of stops carried by said supports, a series of sliding levers, each lever having a bifurcated end, stops on both members of the 60 bifurcated ends of the levers for engaging the stops upon the rack, means for releasing the carriage to permit it to run free, wedge-shaped members on the opposite sides of said levers compelling the operation of said 65 means when the levers are slidingly moved in either direction, said levers having registering slots therein, and a rod extending through all of the slots and compelling the levers to move horizontally, substantially as 70 described.

21. In a tabulating device for typewriters, the combination of a carriage, supports thereon, a tabulator rack carried by said supports, a series of sliding levers, each lever 75 having a bifurcated end, pivoted rocking keys operating said levers, means for releasing the carriage to permit it to run free, wedge-shaped members on the opposite sides of said levers compelling the operation of 80 said means when the levers are slidingly moved in either direction, said levers having registering slots therein, and a rod extending through all of the slots and compelling the levers to move horizontally, substantially as 85 described.

In testimony whereof, I have signed my name to this specification in the presence of two subscribing witnesses.

WILLIAM ERWIN.
